JET-PRODUCING SYRINGE FOR AN ORAL HYGIENE APPLIANCE

Samuel J. Koch, New York, N.Y.

(999 Green St., San Francisco, Calif. 94133)

Filed Nov. 8, 1966, Ser. No. 4,583

Term of patent 3½ years

(Cl. D24—1)

FIG. 1 is a front view of a jet-producing syringe for an oral hygiene appliance showing my new design.

FIG. 2 is a right side view of FIG. 1.

FIG. 3 is a left side view of FIG. 1.

FIG. 4 is a top view thereof.

FIG. 5 is a bottom view thereof.

The dominant features of my design reside in the portions shown in full lines. The portions disclosed in broken lines in FIG. 1 are omitted in FIGS. 2 through 5 for convenience of illustration.

I claim:

The ornamental design for a jet-producing syringe for an oral hygiene appliance, substantially as shown and described.
